HAIR CURLING AND WAVING DEVICE

Thomas McArdle, New York, N. Y.

Application June 23, 1932. Serial No. 618,837

8 Claims. (Cl. 132—38)

This invention relates to improvements in hair curling and waving devices.

The primary object of the invention resides in a hair curling or waving device on which the hair 5 of a head may be rolled to produce long or short curls depending upon the length of the hair wound thereon. The device is especially designed for the present modern style of hair dressing which requires that the hair of a "growing 10 out bob" be curled upwardly at the nape of the neck although the same may be used for the rolling, curling or waving of the hair at other locations upon the head if desired.

Another feature of the invention is to provide 15 a flexible winding and curling element to which the free ends of the hair may be securely clamped and the same wound thereon by the turning of the element, and which element may be bent to conform to the shape or curvature of the head and 20 remain in such bent position as to set the curl or wave and be comfortable to the user during the time required for the waving or curling operation.

Another object of the invention is the provision of a hair curling or waving device which is simple of construction, inexpensive of manufacture, and which may be successfully used by those unskilled in the art of hair waving.

With these and other objects in view, the invention resides in the certain novel construction, combination and arrangement of parts, the essential features of which are hereinafter fully described, are particularly pointed out to the appended claims, and are illustrated in the accompanying drawing, in which:

Figure 1 is a perspective view showing invention in position for use but prior to the rolling operation.

Figure 2 is a similar view, but showing the hair waving device with the hair rolled thereon.

Figure 3 is a side elevational view of the hair waving or curling device per se, but showing the same in bent position.

Figure 4 is an enlarged vertical longitudinal view but showing the device in its normal unbent condition.

Figure 5 is an end elevational view.

Figure 6 is an enlarged vertical transverse sectional view on the line 6—6 of Figure 4.

Referring to the drawing by reference characters, the numeral 10 designates my improved hair waving or curling device in its entirety which includes a flexible resilient elongated tubular member 11 which is in the form of a coil spring, 55 the convolutions of which are in contact with

each other. A covering of flexible and expansible material such as rubber 12 encloses the member 11, and the said member by itself has a tendency to assume a straight position. However, this is not possible when the member 11 is flexed for the 60 reason hereinafter to be explained.

Associated with the flexible tubular member 11 is a flexible non-resilient member 13, the same being formed from a single length of wire, the central portion of which is convoluted as at 14, 65 the said convolutions being spaced as best seen in Figure 3 of the drawing. The portions 15 of the wire extend toward opposite ends of the member 11 and are provided with outwardly extending humps 16, while the free ends of the wire 70 are bent upon the portions 15 to provide enlarged loops 17 to enable the terminal ends 18 to extend into opposite ends of the tubular member 11. The terminal ends 18 of the wire are of a length to overlap each other and to extend approximately the length of the tubular member 11. Slidable upon opposite ends of the member 11 and on the portions 15 are clamping rings or 75 eyes 19 which when slid inwardly over the humps 16 tend to hold the convoluted portions 14 into clamping engagement with the flexible member 11. By extending the terminal ends 18 of the wire into the flexible member 11, the same act to restrain the return of the flexible resilient member 11 to a straight position after flexing of the same, thus the device will remain in any position to which it is bent irrespective of the action of the resilient member 11.

In Figure 1 of the drawing I have illustrated 90 the use of the hair waving device 10 preparatory to the forming of the curls or waves. As before stated, the device is especially adapted for forming curls at the nape of the neck and therefore the free ends of the hair at that portion of the head are inserted between the convoluted portions 14 and the flexible resilient member 11, the rings 19 being slid to their outermost position in order that the ends of the hair may be readily inserted, it being understood that the device is in a straight 95 position such as illustrated in Figures 1 and 4.

After the hair has thus been inserted, the rings 19 are slid inwardly over the hump 16 so as to cause the convoluted portion 14 to coact with the member 11 to clamp the hair. The ends of 100 the device are then grasped by the fingers of the hands of the operator, and the entire device rolled upwardly in order that the hair will roll or be wound upon the members 11 and the convoluted portions 14 of the member 13. During the 110 winding operation, certain of the hair winds upon

the convolutions 14 which tends to prevent the spreading of the hair outwardly toward the ends of the hair curler during the winding operation. When the hair has been wound, the device is flexed or bent to a position to conform to the curvature or shape of that portion of the head adjacent which it is disposed. This is clearly illustrated in Figure 2 of the drawing. When thus flexed or bent, the wound hair will remain set, and after remaining in position the required length of time, the device is rolled downwardly to unwind the hair therefrom, and when fully unwound, the device is removed and the hair will of course return to its upwardly curled position.

15 As previously stated, the device is not limited to the curling of the hair adjacent the nape of the neck, but may be used for forming either long or short curls at any location upon the head of a user.

20 While I have shown and described what I deem to be the most desirable embodiment of my invention, I wish it to be understood that various changes that come within the scope of the appended claims may be resorted to if desired.

25 Having thus described the invention, what I claim as new and desire to secure by Letters Patent is:—

1. A hair curling device comprising an elongated flexible element having openings in opposite ends thereof, a convoluted member extending lengthwise of said flexible element with its opposite ends extending into the opposite open ends of said flexible element.

2. A hair waving device comprising a flexible tubular resilient elongated body member, and a convoluted member, the ends of said convoluted member being bent upon themselves and extending into opposite ends of said body member.

3. A hair waving device comprising a flexible resilient tubular member, a flexible convoluted member, extension portions at opposite ends of said convoluted member bent upon themselves and extending into opposite ends of said convoluted member.

4. A hair waving device comprising a flexible resilient tubular member, a flexible convoluted member, extension portions at opposite ends of said convoluted member bent upon themselves and extending into opposite ends of said convoluted member, and clamping rings slidably mounted on said extension portions and said tubular member.

80 5. A hair waving device comprising a flexible resilient tubular member, a flexible convoluted member, a covering of flexible material enclosing said convoluted member, extension portions at opposite ends of said convoluted member bent upon themselves and extending into opposite ends of said flexible tubular member.

85 6. A hair waving device comprising a flexible tubular springy member, a length of bendable nonresilient wire, the major portion of which is convoluted, the end portions of said wire being bent upon themselves and extending into opposite ends of said tubular springy member, and means for securing the convoluted portions of said wire in clamping engagement with said flexible tubular member.

90 7. A hair curling device comprising a flexible body member and a flexible convoluted clamp between which loose ends of hair are adapted to be spread and clamped and around which the hair to be curled is wrapped, said hair curling device being held in position upon the head of the wearer by bending the clamp and the body portion as a unit in conformation with the wearer's head.

95 8. A hair curling device comprising a normally straight flexible body portion and a convoluted clamping member carried thereby and arranged in parallelism therewith between which loose ends of hair are adapted to be spread and clamped, the hair to be curled being wrapped about both the body portion and clamp, said hair curling device being retained in position by bending the same into conformation with the head of the wearer.
